UNITED STATES PATENT OFFICE.

JACOB L. STAIR, OF CHICAGO, ILLINOIS.

DESIGN FOR A REFLECTOR.

Application filed January 21, 1924. Serial No. 8,364. Term of patent 7 years.

To all whom it may concern:

Be it known that I, JACOB L. STAIR, a citizen of the United States, residing at Chicago, in the county of Cook and State of Illinois, have invented a new, original, and ornamental Design for a Reflector, of which the following is a specification, reference being had to the accompanying drawings that form a part thereof.

Figure 1 is a side elevation of my design for a reflector.

Fig. 2 is a vertical section thereof taken on line 2-2 of Fig. 1 and drawn to an enlarged scale.

What I claim is:

The ornamental design for a reflector, as shown.

In testimony whereof, I have hereunto set my hand and seal at Chicago, in the county of Cook and State of Illinois this 9th day of January, 1924.

JACOB L. STAIR.
